UNITED STATES PATENT OFFICE.

PIERRE J. E. E. CHAMBOST, OF LIVERPOOL, ENGLAND.

LIQUID-FUEL FURNACE.

SPECIFICATION forming part of Letters Patent No. 655,757, dated August 14, 1900.

Application filed December 28, 1897. Serial No. 663,934. (No model.)

To all whom it may concern:

Be it known that I, PIERRE J. E. E. CHAMBOST, a citizen of the Republic of France, residing at 11 Rumford street, Liverpool, in 5 the county of Lancaster, England, have invented certain new and useful Improvements in Liquid-Fuel Furnaces, of which the following is a specification.

This invention has been patented in Great 10 Britain, No. 29,000, dated December 17, 1896.

This invention relates to furnaces of steam-generators and heating-furnaces for burning hydrocarbon liquid of the heavy kinds or of any density.

15 The invention will be described with reference to the accompanying drawings, which illustrate a furnace provided with the invention.

In the drawings, Figures 1 and 2 are a sectional elevation and a part sectional and end view, respectively, of a furnace, illustrating the improvement. Fig. 3 shows a detail connected with the oil-supply pipe. Figs. 4 and 5 are a longitudinal section and cross-section, 25 respectively, of a modified form of vaporizing vessel.

Referring to the drawings, the whole apparatus is placed in the furnace-front or brick-work X, and in the lower part of the furnace 30 two vaporizing chambers or cylinders A are provided and placed in a setting or retort of brickwork I, with a narrow space I' around it and with openings i at the bottom for the heating gas jets or flames and other openings 35 i' at the top. Above these are the burners Y, communicating with the cylinders A by the pipes D E J. In the interior of the vessels A there is a central screwed shaft B, with its ends centered and supported by the covers a 40 of the cylinders, and on this shaft a number of diaphragm-plates b are supported. By mounting these plates b on the screwed shaft any number can be used to suit the quality 45 of oil used and they may be adjusted longitudinally to any position desired. The upper and lower edges of the alternate plates b are cut away, as shown, to make a zigzag course for the oil-vapors. The oil is delivered to the cylinders A by a pipe C, which 50 has an automatic controlling-valve operated as hereinafter described and shown in Fig. 3. The cylinders A are heated by some of the

vapor made in the apparatus, which is burned at the burners G on the pipes H, which are connected with the vapor-supply pipe D by 55 the pipe F. A drain-cock H' is located at the lower end of pipe F, by which any settling may be withdrawn. The heat of the flames of those burners G passes through the space I', around the cylinders A, and then out by 60 the passages i' into the furnace proper.

In operation both or one of the cylinders A may be used at a time; but the pipes D, D', and H, connected with their respective vessels, being provided with cocks d d' and 65 h h', respectively, one of the cylinders can be cut off from connection with the pipes E J and the burners Y while the other is in action. In either case all the burners Y are always in action. In action, therefore, when 70 one cylinder is in use one set of valves d and h or d' h' would be closed and the other set, connected with the other vaporizing-cylinder A, open, and assuming the apparatus to be going the bulk of the vapor generated would 75 pass to the burners Y and partly to the burners G. The vapor-flames from the burners G, acting on the cylinder A, passing up around the cylinder A, through the narrow 80 passage under the brick setting or lining I, easily heats it up to the required high temperature.

To cause the apparatus to work regularly, the amount of liquid hydrocarbon fed to the vaporizing-cylinder must be in proportion to 85 the volume of vapors passing to the burners by the pipe D, and the pressure in the cylinder must be constant, and for this purpose the valve shown in Fig. 3 is interposed between the liquid-hydrocarbon-supply pipe 90 (the oil in which would be under a suitable pressure) and the vaporizing-cylinder, which effects this object in the manner I will now describe. The valve consists of a casing containing two valves K and L, seated in opposite directions and with a spring l between them, and the stem k' of the valve K projects into a hole L' in L. The seat of valve K has grooves or channels k in it, which allow sufficient hydrocarbon to pass at any time when 95 the valve is on its seat. The action of this valve is as follows: When the pressure on the supply side of the valve L exceeds that in the cylinder A, it opens and pressing on

the valve-stem k' presses K onto its seat, thus closing the valve and passage for hydro-carbon, except by way of the grooves k , to the cylinder. On the other hand, if the pressure in A exceeds that on the valve L the lower valve K is raised from its seat, so closing the valve L and shutting off the supply of oil until the pressure in C again becomes greater than that in the cylinder. The oil then passes into the cylinder and is vaporized and passes through the several compartments between the plates b and becomes thoroughly gasified under the influence of the high temperature therein. If carbon or coke be deposited, it is deposited on the plates and shafts and inner surface of the cylinder A, and after lengthened use of the apparatus a cylinder can be cut off by closing the valves d and h or d' h' of this cylinder and cleaned by opening out one end cover a , while the other cylinder can be in action.

As will be seen by the drawings, all the burners will be fed by vapor from either of the cylinders A, and consequently they are operative no matter which of the cylinders is in action.

The burners Y are of a special kind and are specially constructed to prevent their becoming dirty or greasy or their regulating devices becoming choked or jammed owing to the high temperatures to which they are subjected, as happens with burners hitherto proposed. To obviate these difficulties, the valve-box N is provided with a hollow nozzle-plug M, screwed into N, with one or more holes in its end, the length of the holes being very short, as shown, and are in consequence not likely to clog and can be easily cleaned.

The inner edge of the hollow plug M constitutes a seat, in connection with which a broad tapered valve O on the end of a valve-spindle o' works, which valve-spindle passes through a stuffing-box P, having within it a separate gland p , and the stem o' is screwed outside this gland and is therefore out of contact with the heat and in a cool part, so that clogging of the screw is avoided, as the screw is kept away from the vapor and heat.

The burners may be arranged as shown in

Figs. 1 and 2 or a greater or less number used and arranged in any desired order.

The modification of the vaporizing vessel A (shown in Figs. 4 and 5) consists in having a D-shaped vessel with the lower edges of the divisions B standing above the floor, while the floor of the retort itself is ribbed, as shown, transversely.

The apparatus may be started by heating up the cylinder by ordinary lighting or by burning spirit or the like under it, and it may be charged with volatile spirit, which starts it, and when hot enough the heavy hydro-carbon liquid is turned on.

The invention is not limited to the form of details, and sometimes I only use one cylinder.

What I claim in respect of the herein-described invention is—

1. In apparatus for heating steam-generator or other furnaces by oil-gas, a pair of oil-vaporizing cylinders A, with internal diaphragms b carried from a central spindle B; and oil-inlets and vapor-outlets for said cylinders; substantially as and for the purposes set forth.

2. In apparatus for heating steam-generator or other furnaces by oil-gas, the oil-vaporizing cylinders A, with internal diaphragms b , and threaded shaft B carrying said diaphragms, and on and by which they can be adjusted longitudinally; and oil-inlet pipe C at one end, and vapor-outlet pipe D at the opposite end; substantially as set forth.

3. In apparatus for heating steam-generator or other furnaces by oil-gas, the oil-vaporizing cylinder A with internal diaphragms b , and the threaded shaft B, carrying said diaphragms and on and by which they can be adjusted longitudinally, and oil-inlet pipe C at one end, and vapor-outlet pipe D at the opposite end; substantially as set forth.

In testimony whereof I have hereunto set my hand in presence of two subscribing witnesses.

PIERRE J. E. E. CHAMBOST.
